A. RUEBSAMEN,
HIGHWAY GUIDEPOST.
APPLICATION FILED APR. 14, 1921.

Patented Apr. 11, 1922.

Fig. 1.

UNITED STATES PATENT OFFICE.

ALBERT RUEBSAMEN, OF DECATUR, ILLINOIS, ASSIGNOR TO DECATUR SUPPLY & FARE REGISTER COMPANY, A CORPORATION OF ILLINOIS.

HIGHWAY GUIDEPOST.

1,412,632.

Specification of Letters Patent. Patented Apr. 11, 1922.

Application filed April 14, 1921. Serial No. 461,291.

To all whom it may concern:

Be it known that I, ALBERT RUEBSAMEN, a citizen of the United States, residing at Decatur, in the county of Macon and State 5 of Illinois, have invented certain new and useful Improvements in Highway Guideposts, of which the following is a specification.

The invention relates to improvements in 10 highway guide posts.

One of the objects of the invention is to provide a highway guide post by means of which a vast amount of detailed information, pertaining to the location in which 15 the post is situated, characteristics of the contiguous country through which the designated routes pass and distances to the adjacent towns, villages, cities reached thereby, reciting the location of garages, hotels, and 20 addresses of physicians, highway superintendents, magistrates, and other persons and things of interest to a travelling stranger in a strange neighborhood is available.

Another object is to provide a highway 25 guide post in which a series of printed cards containing desired information are housed and protected from weather, but readily available when required.

Another object is the provision of a high- 30 way guide post having card holding means normally within a housing which may conveniently be moved outside the housing for inspection and which will automatically return to the housing when released.

Another object is to provide in a device 35 of the character described a rotatable housing, to contain miscellaneous information, that may readily be moved on its axis for more convenient inspection of the subject 40 matter of the cards therein.

Another object is to provide card holding frames in which cards are interchangeable for substitution of new cards for older ones when required.

Another object is to provide a guide post 45 in which general information, such as the number or other designation of the routes and geographic direction, such as North, South, East and West, are placed on fixed 50 parts of the post and more specific information, characteristic of the particular situation, is contained in a weather-proof housing.

Other, further and more specific objects of the invention will become readily apparent to persons skilled in the art, from a consideration of the following description, when taken in conjunction with the drawings, wherein:—

Fig. 1 is a central vertical section of the device showing one of the frames moved to 60 a position with the information card on the outside of the housing for convenient inspection.

Fig. 2 is a transverse section taken on line 2—2 of Fig. 1.

In both views the same reference characters are employed to indicate similar parts.

In the drawings 3 is a post to be placed 70 in the ground at selected locations along a highway, and particularly is it designed to be used at the points where highways cross, as a means for furnishing information to travelers along either one of the highways.

4 is a threaded cap for attachment to the upper end of the post 3. A rod 5 is properly secured to the cap, shown to be threaded thereon and held in place by a nut 6. The upper end of the rod is threaded, as at 7, to receive and hold a roof structure 8. The 80 roof structure has a central boss 9 and four inclined walls 10. A cross section of the roof at right angles to that shown in Fig. 1 will appear substantially as shown in Fig. 1, that is to say, the four portions 10 are inclined from the center 12 to the respective outer edges.

Fixed to the upper central portions of the inclined part 10 are sign boards 13 and 14 bearing the route numbers and the directions with respect to the point at which the device is located. One of these signs will bear the route number together with the word "North" and the one on the opposite side with bear the same route number with 90 the word "South", whereas those that are arranged at right angles will bear the respective number of another route with the words "East" and "West", respectively.

The roof, together with the rod 5, are fixed 100 to the post 3, and when once adjusted to show the directions of the compass, they are not thereafter molested.

A normally closed housing 15 is rotatable

upon the rod 5, and located between the roof and the post 3, which consists of the bottom plate 16 centrally perforated, as at 17, to be rotated about the post and a top plate 18, similarly perforated, as at 19, for the same purpose. Between the top and bottom plates are corner posts 20, 20^a, 20^b and 20^c, secured to the plates 16 and 18, at their respective corners.

10 There are four panels or closures 21, 21^a, 21^b and 21^c hinged, or pivoted, to the respective adjacent posts. Each of the panels consists of a rectangular frame 22, having side members 23 and 23', each of which is provided with a trunnion 24, 24', located above the center of gravity of the panel or closure and in horizontal planes, so that when the door is swung outwardly, as shown in Fig. 1, it will automatically 15 move back into closed position when released. Between the members of the frame 22 is contained a plate 25, which may be of steel, or other suitable material, and in the rear of the plate, in suitable channels, is located a renewable card 26, fixed in place by a strap 27 secured to one member of the frame, so as to hold the card in place. Information, regarding characteristics of the respective routes, is to be printed upon 20 the card as shown at 28. As the information may be varied from time to time the card is insertible in the frame and new cards may be substituted by removing and replacing the strip 27. The bottom frame member 22 may be weighted, as by means 25 of a weight 29, so that the door will be automatically closed and held closed by the excessive weight.

When a person traveling along a highway 40 desires to consult the cards within the housing 15, he seizes the knob on the weight 29 and lifts the door into position shown on the right of Fig. 1, whereupon the printed information contained upon the card, and 45 which is normally upside down when the door is closed, will be presented in a legible manner so that it may be read by any person confronting the card.

The housing 15 is rotatable so that if the 50 information contained upon one card is not all that is required the housing may be rotated for more convenient examination of the other cards as when a person approaches the structure in an automobile, in a 55 vehicle of any description, or on horseback, without the necessity of going around the post.

The housing 15 is absolutely water-proof and not accessible by insects, birds, or the 60 like, and when made of the proper material, will endure for a protracted period of time without attention or repairs.

By having the cards contained normally 65 inside of the housing they are protected from the deleterious effects of the weather

and from injury by persons, maliciously inclined, passing along the highway.

Signs bearing instructions relating to required detours may be suitably supported on the device and removed when the necessity 70 for their presence has been restored to normal conditions.

While I have shown an exemplification of the invention which is rectangular in shape, it is, of course, manifest that the invention 75 is not limited to the exact proportion or configuration shown, but is only limited by the scope of the appended claims. The housing and the cooperating plates may, of course, be made as large as desired and any 80 number required may be contained therein.

Having described my invention what I claim as new and desire to secure by Letters Patent, is:—

1. A highway guide device comprising a 85 fixed structure having spaces wherein to designate information of substantially unchangeable character and a closed rotatable housing within which are contained a plurality of like renewable surfaces bearing specific information characteristic of the adjacent country through which the designated routes pass; means to independently display the surfaces outside the housing for inspection and automatic means to return each 90 characterized surface to the housing when released.

2. A highway guide device comprising a 95 fixed structure having spaces wherein to designate information of substantially unchangeable character in combination with a housing comprising a frame having uniformly spaced apart vertical posts; doors automatically movable to closed position between adjacent posts to form a closed housing; hinges above the center of gravity of the doors to pivot them in horizontal planes to automatically maintain them in vertical planes and guiding information contained on the inside of the doors readable and legible when the doors are inverted for inspection and the information-bearing surfaces thereof thus moved outside of the housing.

3. A highway guide device comprising a 115 post; a frame thereon and fixed thereto comprising a vertical rod secured to the post and extending thereabove; a roof fixed to the upper end of said rod, bearing visible indications of route and directions, in combination with a rotatable housing between the 120 roof and post comprising a bottom and a top plate rotatable about said rod; corner posts connecting the bottom and top plates together; swinging closures to form a normally closed housing pivoted to the adjacent 125 posts, arranged to swing outwardly and bearing on their inside surfaces information respecting the routes indicated by the structure, and arranged to swing inwardly to close the housing when released.

4. A highway guide device comprising a fixed structure having spaces wherein to designate information of substantially unchangeable character and a closed housing; a series of doors hinged on horizontal pivots located above their centers of gravity to automatically close the housing; means to hold a card bearing specific information on the back of each door and means to rotatably support the housing.
5. In testimony whereof I hereunto subscribe my name.

10

ALBERT RUEBSAMEN.
